FOREIGN PATENT DOCUMENTS

CN 203584275 5/2014

Primary Examiner — Celia Murphy*Assistant Examiner* — Clare Ann Gannon(74) *Attorney, Agent, or Firm* — Head, Johnson, Kachigian & Wilkinson, PC(57) **CLAIM**

The ornamental design for a cord guide for a roman blind system, as shown and described.

DESCRIPTION

FIG. 1 is a top view of the cord guide for a roman blind system of the present invention;

FIG. 2 is a bottom view thereof;

FIG. 3 is a front view thereof;

FIG. 4 is a back view thereof;

FIG. 5 is a perspective front view thereof;

FIG. 6 is a perspective rear view thereof;

FIG. 7 is a further perspective front view thereof;

FIG. 8 is a further perspective rear view thereof;

FIG. 9 is a left side view thereof; and,

FIG. 10 is a right side view thereof.

Portions of the article shown in broken lines are not included in the claim or depict environment that is not included in the claim.

1 Claim, 10 Drawing Sheets(56)
